PACKAGING CIGARS

James C. Draper, Toledo, Ohio, assignor to
 Owens-Illinois Glass Company, a corporation
 of Ohio

Application December 16, 1940, Serial No. 370,307

20 Claims. (Cl. 226—2)

My invention relates to a method and apparatus for packing cigars and other articles. More particularly, the invention as herein illustrated is designed and adapted for packing cigars in cylindrical jars. An object of my invention is to provide a practical and efficient apparatus by which cigars may be rapidly packed in cylindrical glass jars or other cylindrical containers with the cigars symmetrically arranged in keeping with conventional requirements.

At the present day cigars are being packed commercially in cylindrical glass jars, usually with a standard pack of 50 cigars in a jar. In accordance with approved methods, a ring or layer of cigars is first placed in position to line the inner cylindrical wall of the container, and thereafter a group of cigars, sufficient in number to complete the pack, is placed in the space surrounded by said ring. The outer ring of cigars is preferably arranged with the labels facing outwardly and placed so that they may be seen through the transparent wall of the container.

An object of the present invention is to provide an improved apparatus for packing and arranging cigars in keeping with the requirements above indicated. Another object of the invention is to provide such an apparatus adapted for packing cigars on the like in a jar or container, the mouth of which is of smaller diameter than the body of the jar. In practice, the diameter of said mouth is usually about equal to the diameter of the space defined or surrounded by the cigars forming the outer ring or layer of the pack.

A further object of the invention is to provide a novel method of introducing and arranging the cigars in the container. More specifically, the invention provides a method and apparatus by which the cigars of a group sufficient in number to form the outer layer or ring of the pack, are arranged spirally in a magazine which is then introduced into the container. The cigars are then by a spiral movement ejected from the interior of the magazine and guided into an annular space provided between the walls of the magazine and the container. Thereafter the complementary group of cigars required to complete the pack is transferred as a unit from a second magazine into the container.

Other objects of the invention will appear hereinafter.

Referring to the accompanying drawings which illustrate an apparatus for use in packing cigars in cylindrical jars in accordance with the present invention:

- 5 Fig. 1 is a front elevation of the apparatus;
 Fig. 2 is a plan view;
 Fig. 3 is an elevation on a larger scale of a magazine shown in Figs. 1 and 2;
 Fig. 4 is a sectional elevation of the spiral magazine, the section being taken at the line 4—4 on Fig. 2;
 Fig. 5 is a section at the line 5—5 on Fig. 3;
 Fig. 6 is a section at the line 6—6 on Fig. 3;
 Fig. 7 is a section at the line 7—7 on Fig. 2, showing the drum or magazine for holding the inner group of cigars;
 Fig. 8 is a section at the line 8—8 on Fig. 7; and
 Fig. 9 is a sectional detail taken at the line 9—9 on Fig. 7.
- 10 The apparatus comprises a supporting structure including a floor 10, side walls 11 and 12, a front end wall 13 and rear wall 14. The articles 15 which are to be packed, here shown as cigars, are placed in a row on a table 16, with the labels 17 arranged in line and facing upwardly. The cigars are advanced from the table to a runway or channel including a stationary section 18 and hinged chutes or sections 19 and 20 through which the cigars are directed to magazines 21 and 22. A predetermined number of cigars is placed in each magazine and thereafter transferred to a container 23 (Figs. 4 and 8).

15 The magazine 22, herein referred to as the spiral magazine, has a fixed mounting and comprises a circular front end plate 24 attached by screws 25 to the front wall 13. The rear end plate 26 of the magazine is secured by screws 27 to a cylindrical hub 28 extending centrally through the magazine, with the forward end portion 29 of the hub extended through and beyond the front end plate and of reduced diameter. The magazine 22 comprises an outer substantially cylindrical shell 30 formed of sheet metal. Within the shell 30 is a spirally arranged sheet metal piece 31, the outer end 32 (Fig. 4) of which is attached to the shell 30, the inner end being attached at 33 to the hub 28. The shell 30 and the spiral 31 are anchored 20 in the end walls of the magazine and are so

shaped that they provide a spiral channel or passageway 34. The outer end of the spiral channel opens upwardly at the upper side of the magazine and is arranged to align with the forward end of the chute 20 as shown in Fig. 4.

The channel sections 18, 19 and 20 are formed with vertical side walls 35 and inturned flanges 35' at the upper margins of the side walls, to provide guideways for the cigars. The flanges 35' of the chute 20 are extended to meet the end 36 of the shell 39. Beneath this curved extension is a curved plate 37 which, as shown in Fig. 4, has one edge adjacent the floor of the chute 20 and the opposite edge resting on the inner spiral wall 31. The plate 37 thus serves to guide the cigars from the chute 20 into the spiral passageway 34. A strip of metal 38, attached to the spiral strip 31, abuts or aligns with the end surface of the section 31 providing a smooth surface for guiding the cigars into the chute. The section 37 is hinged to swing about its upper edge as a pivot so that said plate may serve as a pusher for moving the last cigar of the ring pack outwardly into position as more fully set forth hereinafter. The pivot pin 39 for said pusher (see Figs. 3 and 5) extends through the end plate 24 of the magazine and has attached thereto a rock arm formed with a finger-piece 40. A coil spring 41 held under compression holds the plate 37 in its lowered position (Fig. 4).

The mechanism for transferring the cigars from the spiral magazine and arranging them in a ring within the container 23 will now be described. Such mechanism includes a hand crank 42 with a handle 43, said crank being attached to a hub 44 mounted for rotation on the hub shaft 29 and held thereon by a screw 45. Rods 46 and 47 are secured to the hub 44 and project outwardly therefrom in diametrically opposite directions, said rods being in alignment. A frame slidable lengthwise of the rods 46, 47, comprises side bars 48 attached to end blocks 49 and 50 journaled for sliding movement respectively on the rods 47 and 46. The end block 50 has secured thereto a paddle 51 which extends into the spiral channel 34 (see Figs. 4 and 6). The paddle is formed with a reduced end or neck portion 52 which extends through a spiral slot 53 formed in the end plate 24 of the magazine, said slot 53 extending along the spiral chute 34. The paddle serves as a means for ejecting the cigars from the magazine as hereinafter described. Rolls 54 are mounted on the end block 50 of the slide frame and run on opposite sides of the crank 42 for guiding the slide frame in its reciprocating movements. It will be seen that when the hand crank 43 is rotated in a counter-clockwise direction from the position shown in Fig. 3, the paddle 51 will be moved in a spiral path from the Fig. 4 position and thereby eject the cigars from the magazine.

The second container or magazine 21 is in the form of a cylinder and has a fixed mounting on the front wall 13, being provided at one end thereof with an annular flange 55 by which the magazine is attached to the wall 13. The opposite end of the cylinder comprises a tapered section 56 which is adapted to fit into the neck of the container 23 and serves to guide the cigars into the container and also to compress them slightly, thereby facilitating the placing of the cigars in position within the container. After a complement of cigars necessary to complete the pack has been placed in the magazine 21 and the jar 23 brought into position (Fig. 8), the cigars are transferred to the jar by means of a disk plunger

57 to which is attached an operating rod 58 extending through an opening in the front wall 13 and slidably lengthwise in a bearing sleeve 59. A ball handle 60 is provided at the outer end of the rod.

A swinging cradle 61 (Figs. 1 and 2) provides a support for the jar or container 23 during the packing operation and serves to hold the container in line with the magazines. Said cradle 10 includes end bars 62, the upper surfaces of which are convexly curved to conform to the curvature of the container. Said end bars are pivotally connected to cylindrical side bars 63 formed on the upper ends of a pair of parallel swinging members or links 65, the lower ends of which are pivoted at 66 to brackets 67. A stationary support for the container 23 is arranged directly beneath the magazine 22. It comprises a pair of rolls 68 mounted on end supports 69.

20 The section 20 of the horizontal chute is mounted to swing about the axis of a pivot rod 70 (Fig. 7), permitting the forward end of the chute to be lifted to the dotted line position (Fig. 4), thereby permitting a jar 23 to be moved forward to surround the magazine 22. The swinging movement of the chute 20 is caused by the neck or shoulder of the jar engaging a cam 71 attached to the chute. The intermediate section 19 of the chute is mounted to swing about the axis of the 25 pivot pin 72 (Fig. 7) downwardly from its horizontal position to the dotted line position for directing the cigars into the magazine 21. The section 19 is normally held up in its horizontal position by a coil spring 73 attached at one end to a 30 pin 74 projecting from the pivot rod 72, the other end of the spring being anchored to the wall 11. When the forward section 20 is swung upward as above described, an arm 75 thereon (Figs. 2 and 7) tilts the section 19 downward. The arm 75 is 35 rigidly attached to the section 20 and projects rearwardly therefrom over a flange 76 (Fig. 2) on the section 19.

The magazine 21 is formed with a longitudinal slot or opening 77 in position to permit entrance of 40 the cigars as they are discharged from the chute 19. I have found it advisable to close the opening 77 after the cigars have been placed in the magazine in order to prevent cigars from being caught 45 therein and interfering with the transfer of the cigars to the jar. For this purpose a slide plate 78 is mounted for sliding movement circumferentially of the magazine wall in guideways 79 and 80 (Fig. 9). This movement is effected automatically by means of a link 81 connected to lugs 50 on the chute 19 and plate 78 respectively. When the chute 19 is moved downward the plate 78 is 55 also carried downward and thereby uncovers the opening 77.

Operation

60 The operation may be described as follows: The predetermined number of cigars required to form the outer ring of the pack is moved forward from the table 16 through the chutes 18, 65 19 and 20 and into the spiral magazine, thereby filling the latter as shown in Fig. 4. The paddle 51 provides a stop at the inner end of the spiral channel. An empty jar 23 is placed on the cradle 61 and while the latter is in line with the support 68, 69 (Fig. 2), the jar is moved forward 70 endwise so that the magazine 22 is positioned within the jar. The said movement of the jar at the same time cams the chute 20 upward out of the way. The operator now rotates the crank 75, 42 in a counter-clockwise direction and thereby

causes the paddle 51 to move spirally outward along the channel 34 and thereby push the cigars out of the magazine into the annular space between the outer wall of the magazine and the cylindrical wall of the container. When the crank has reached the limit of its rotative movement, which may be determined by the paddle striking the end of its spiral groove 53, all of the cigars have been placed substantially in position except the last one which is now in engagement with the hinged section 37. The operator now depresses the finger-piece 40 (Fig. 3) which swings the section 37 outwardly about its pivot and thereby forces the last cigar into position within the ring. This last cigar while thus being wedged into position between the adjoining cigars, applies a moderate lateral pressure which is distributed to the entire ring of cigars and holds them in position. It will be noted that the labels 17 will all face outwardly so that they are readily seen through the glass wall of the container.

The jar is now withdrawn endwise from the magazine 22 back onto the cradle 61 and the latter is then swung to the left (Fig. 1) to bring the jar into line with the second magazine 21. The jar is then moved forward a short distance so that the tapered end 56 of the magazine (Fig. 8) is positioned within the neck of the jar. The magazine 21 may be filled either before or after the spiral magazine. A predetermined number of cigars is moved through the chute 19 into the magazine 21, said number being the quota required to complete the pack. When the jar 23 with the outer ring of cigars packed therein has been brought into register with the magazine 21, as above described, the operator by means of the handle 60 moves the plunger 57 forward, thereby forcing the group of cigars from the magazine into the jar, thus completing the pack.

Modifications may be resorted to within the spirit and scope of the appended claims.

I claim:

1. The method of packing articles in a container which comprises introducing a spirally arranged group of the articles into the container and then moving said articles spirally into position to form a ring of the articles extending along the inner wall of the container, and thereafter introducing additional articles into the container to complete the pack.

2. The method of packing a cylindrical container which comprises arranging a predetermined number of the articles in a spiral group, introducing said group as a unit into the container, moving said group spirally into position to form a ring of the articles extending along the wall of the container, and thereafter introducing an additional number of articles to fill the container and complete the pack.

3. The method of packing cigars or articles of similar shape into a cylindrical container, which method comprises introducing into the container a group of the articles consisting of a predetermined number of the articles sufficient to form a ring extending along the inner cylindrical wall of the container, with said group positioned to leave an empty annular space between said wall and the group of articles within the container, and advancing the articles in series in a predetermined path by which the articles are moved into position to form said ring within said annular space.

4. The method of packing cigars in a cylindrical container which comprises arranging a pre-

determined number of the cigars in a row, thereafter introducing said row of articles bodily as a unit into a position within the container to form an empty space between the inner wall of the container and the group of articles, then moving the articles by pressure applied at the end of said row and transmitted to all of the articles, and directing the articles in a predetermined path during such movement into position to form a ring lining the inner cylindrical wall of the container.

5. Packing apparatus comprising a magazine formed with a spiral passageway therein, and means for ejecting from the magazine a row of articles spirally arranged within said passageway, said ejecting means comprising a paddle extending within said spiral passageway adjacent the inner end of said passageway in position to engage behind the innermost article of said row, and means to effect a relative movement of the paddle and magazine by which the paddle is advanced in a spiral path extending along the said spiral passageway and thereby operates positively to force the articles in a spiral pathway out of the magazine.

6. Packing apparatus comprising a magazine having an approximately cylindrical outer shell and an inner spiral wall forming with said shell a spiral channel, said shell having spaced ends providing an opening into said channel, and a section hinged at one end to swing about a pivot adjacent one end of the shell from a position in which it extends across and closes said opening to a position in which its free end engages the spiral wall and the hinged section thereby provides a stationary guiding surface for guiding articles through said opening.

7. Packing apparatus comprising magazines, a sectional chute through which articles are conveyed to the magazines, said chute comprising sections individual to the magazines, means for moving said sections alternatively into operative positions, one of said magazines having an opening through which articles are transmitted from the chute into the magazine, a gate mounted for movement into and out of position to close said opening, and connecting means between said gate and the corresponding chute section for moving the gate to and from the position for closing said opening as said chute section is moved from and to its operative position.

8. Packing apparatus comprising in combination a magazine formed with an interior channel to receive articles, said magazine adapted to be positioned within a container, a chute extending to the magazine for directing articles into said channel, and a cam carried by the chute in position to be engaged by the container when the latter is moved into position to receive the magazine and thereby cause the chute to be cammed away from the magazine and thus permit the latter to enter the container.

9. Packing apparatus comprising a magazine formed with a spiral channel to receive articles and position them in a spiral row within the magazine, a paddle projecting into said channel, spiral guiding means for guiding said paddle in a spiral path through said channel, and means for moving the paddle along said path.

10. Packing apparatus comprising a magazine formed with a spiral channel to receive articles and position them in a spiral row within the magazine, a paddle projecting into said channel, and means for moving and guiding said paddle in a spiral path through said channel, said means

comprising a supporting frame for the paddle mounted to reciprocate transversely of the axis of said spiral, a crank rotatable about said axis, and means providing a driving connection between the crank and said reciprocating frame whereby rotation of the crank causes the paddle to be advanced spirally along said channel.

11. Packing apparatus comprising in combination magazines, a supporting structure on which the magazines are mounted in laterally spaced relation, a cradle for holding a container, said cradle being movable from a position in which a container thereon is held in register with one magazine to a position in which it is held in register with the other magazine, and a pair of parallel links on which the cradle is mounted, said links being mounted to swing the cradle and a container supported thereon from a position of registry with one magazine to a position of registry with the other.

12. Packing apparatus comprising an approximately cylindrical magazine, means by which a spiral channel is formed in the magazine, and means for moving a group of articles spirally out of the said channel into an annular space provided between the outer wall of the magazine and the wall of a cylindrical container in which the magazine is introduced, thereby arranging the articles in a ring, said magazine comprising a section positioned and arranged to form an extension of the inner wall of the channel and engage the last article moving out of the channel, said section being hinged at one end to swing outwardly across the channel and thereby move said last article radially outward into position to complete the ring.

13. Packing apparatus comprising in combination a supporting structure, magazines mounted thereon, a chute comprising aligned sections, one of said sections being arranged to register with one said magazine while the chute sections are in line, means for swinging said last mentioned section away from the magazine to permit a container to be interposed between the magazine and said chute, and means actuated by said last mentioned chute section when swung away from its magazine, to move another section of the chute into position to direct articles into the second magazine.

14. The method of packing articles in a cylindrical container which comprises introducing into the container a group of articles and positioning the group centrally within the container, with an empty annular space between the group and the cylindrical wall of the container, and then moving the articles in a predetermined path into position to form an annular group within said space.

15. The method of packing articles in a cylindrical container which comprises introducing into the container a group of articles and positioning the group centrally within the container,

5 with an empty annular space between the group and the cylindrical wall of the container, moving the articles in a predetermined path into position to form an annular group within said space, and thereafter introducing simultaneously a sufficient number of articles into the container to complete the pack.

10 16. The method of packing articles in a cylindrical container which comprises introducing into the container a group of articles and positioning the group centrally within the container, with an empty annular space between the group and the cylindrical wall of the container, moving the articles in a predetermined path into position to form an annular group within said space, thereafter bringing to the mouth of the container a second group of articles of the required number to complete the pack, and moving said second group bodily as a unit into the container.

15 20 17. The method of packing cigars or similar articles within a container which comprises positioning and arranging a predetermined number of the articles in a spiral row within the container, with an annular space between the walls of the container and the said articles, and moving the articles into said annular space by a simultaneous spiral movement of all of the articles.

25 30 35 18. The method of packing cigars or similar articles within a container which comprises positioning and arranging a predetermined number of the articles in a spiral row within the container, with an annular space between the walls of the container and the said articles, moving the articles into said annular space by a simultaneous spiral movement of all of the articles, and moving the last article of the group into position by forcing it radially outward and thereby compacting the articles in the ring.

40 45 50 19. The method of packing articles in a cylindrical container which comprises introducing into the container a group of articles and positioning the group centrally within the container, with an empty annular space between the group and the cylindrical wall of the container, and then moving the articles in a spiral path from said group into said annular space in succession and along said space into position to form an annular group therein.

55 60 20. The method of packing articles in a cylindrical container which comprises introducing into the container a group of articles and positioning the group centrally within the container, with an empty annular space between the group and the cylindrical wall of the container, moving the articles singly and in succession into said annular space at a predetermined point, and advancing the articles from said point in a predetermined path extending along said annular space and thereby forming an annular group of the articles lining the inner wall of the container.

JAMES C. DRAPER.
